United States Patent Office

Des. 210,655

Patented Apr. 2, 1968

210,655

TRACTOR BODY

Edward J. Lazzaroni, Racine, Wis., assignor to J. I. Case
Company, Racine, Wis., a corporation of Wisconsin

Filed June 29, 1967, Ser. No. 7,636

Term of patent 14 years

(Cl. D14—3)

FIG. 1 is a side elevational view of my design for a tractor body. The side opposite is the same as the side shown.

FIG. 2 is a rear elevational view of FIG. 1.

FIG. 3 is a top plan view of FIG. 1.

FIG. 4 is a front elevational view of FIG. 1.

FIG. 5 is a side perspective view of a fragment of FIG. 4.

I claim:

The ornamental design for a tractor body, substantially as shown and described.
